UNITED STATES PATENT OFFICE.

THEODORE M. FARLEY, OF DIXON, ILLINOIS.

PERFORATING DEVICE FOR MUSIC-SHEETS.

No. 903,963.

Specification of Letters Patent.

Patented Nov. 17, 1908.

Application filed February 17, 1908. Serial No. 416,399.

To all whom it may concern:

Be it known that I, THEODORE M. FARLEY, a citizen of the United States, residing at Dixon, in the county of Lee and State of Illinois, have invented certain new and useful Improvements in Perforating Devices for Music-Sheets; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has reference to machines for producing music sheets of the kind in use in automatic musical instruments, and is designed to be used in connection with a piano or other instrument provided with a key-board, so that the music which is being played on such instrument may be simultaneously reproduced on one or more of the music sheets.

My device is simple and compact in construction, and can be quickly applied to the instrument without injury thereto. The principal part of the machine can also be instantly detached from the piano, at such times as it is not desired to reproduce the music.

In the drawings: Figure 1 is a longitudinal mid-section of my invention, when in position for use. Fig. 2 is a detail of one of the perforating devices, illustrating the manner of operation thereof. Fig. 3 is a front view of one of the levers 29. Fig. 4 is a fragmentary view, in plan, of the perforating mechanism, with some of the parts broken away.

Similar numbers refer to similar parts throughout the several figures.

The device consists primarily of a series of punches, one for each of the keys of the instrument, and means for imparting movement to the punches, upon the corresponding key being operated. As the several perforating devices and groups of mechanism which actuate the same are identical throughout the machine, or are common to all of said devices, the description will be limited to one of the units thereof.

1 represents a bed-plate, supported on legs 2, and mounted on the plate 1 is a cross-plate 3, having a vertical perforation 4. Supported at some distance above the cross-

plate 3 is a cross-plate 5, in which a punch 6 has vertical movement. Immediately above the cross-plate 3 is a cross-plate 7, in a perforation in which the lower end of the punch 6 is normally held, such perforation being in line with the opening 4.

Integral with the punch 6 is an angular arm 8, the end of which passes downwardly through a perforation in the plate 5, parallel with the punch 6, and in rear thereof. The end of the arm 8 is supported by a lever 9, fulcrumed on a rod 10, supported at each end in a bracket 10^a, secured to the frame. A contractile coiled spring 11 is secured at one end to the short end of the lever 9, and at the other end to a rod 11^a, also supported in the brackets 10^a. The latter mechanism operates to hold the punch 6 normally in elevated position, as shown in Fig. 1.

Pivotedly secured to the punch 6, as at a, is a bar 12, having fixed to its upper end an agitator-plate 13, which is provided at its upper end with an upwardly extending key 14. The key 14 is held in a slot 15 in a cross-bar 16, supported in the machine above the cross-plate 5. This permits a limited movement of the key 14 and plate 13 longitudinally of the machine.

Mounted on the plate 1, in front of the punch mechanism above described, is a pair of supports 17, (one only being shown) in which is mounted a rotary shaft 18, to which is fixed a transverse block 19, provided with a plurality of striker-blades 20, which pass in close proximity to the plate 13 upon the rotation of said block. Fixed to the end of the shaft 18 is a sheave 21, by means of which rotation may be imparted to said shaft from the usual motor, or other means.

22 represents the key-bed of a piano, and 23 one of the keys thereof. Supported beneath the key-bed is a rod 24, upon which is fulcrumed a lever 25, upon the forward end of which is supported a pin 26, having its upper end contiguous to the lower face of the key 23, near the forward end thereof. Fixed to the lower face of the key-bed 22 is a support 27, in which is mounted a rod 12, upon which is fulcrumed a bell-crank lever 29, the upper end of which is connected with the rear end of the lever 25 by means of a short rod or link 30. The lower end of the lever 29 is provided with a fork 31, which engages the key 14 of the plate 13. Upon the key 23 being depressed by the operator, the forward end of the lever 25 is forced

downwardly by the pin 26, actuating the lever 29 to throw the key 14 towards the block 19. The upper end of the agitator 13 is thus brought in line with the outer edges 5 of the striker-blades 20, causing such agitator-plate to be forced downwardly, giving to the punch 6 a corresponding downward movement, until the lower end thereof enters the opening in the plate 3. That corner of 10 the plate 13 with which the striker-blades contact is preferably rounded, to facilitate the movement of the blades thereon. When the pressure upon the key 23 is relieved the plate 13 is returned to its former position by 15 means of a coiled spring 32, attached at one end to the plate 13, and at the other to a bracket 33, mounted on the frame of the machine. When the plate 13 is returned to its former position the punch 6 is likewise 20 returned to its normal position by means of the spring 11, as before mentioned. The upward movement of the punch is limited by a cross-bar 33^a, with which the arm 8 contacts.

25 One or more paper sheets 34 are passed through the machine, such sheets passing first over a roller 35, mounted in supports 36, fixed on the plate 1. Above the roller 35 is a similar roller 37, mounted on a shaft 38 which has vertical movement in curved slots 39 in the supports 36, such slots being adapted to support said shaft in their upper ends when the sheets 34 are being first introduced into the machine. The sheets pass 30 from the roller 35 over a drum 40, the ends of which serve to keep the edges of the sheets even, and from such drum said sheets pass between the plates 3 and 7, and beneath the perforating devices. They then 35 pass over a roller 41, mounted in the supports 17, to which roller motion may be imparted to cause the movement of the music sheets through the machine. Above the roller 41 is a roller 42, mounted on a shaft 40 held in curved slots 44 in the supports 17, similarly to the shaft 38. The rollers 37 and 42 are of sufficient weight to keep the sheets 34 pressed tightly together in their 45 progress through the machine. From the rollers 41 the sheets 34 pass over a shoulder 45, above which a knife 46 is supported in a frame 47, and adapted to be forced downwardly past the shoulder 45, severing the sheets 34 at that point, when the piece is 50 complete. Nothing is broadly claimed herein on the mechanism by means of which the music sheets are caused to pass through the machine, nor on the mechanism by which such sheets may be cut, and further details 55 of the operation thereof are not deemed necessary.

56 48 represents a stand, or support, in which are held a plurality of reels 49 from which the sheets 34 are fed into the machine. A 60 portion of one of the sheets 34 is shown in

Fig. 4, with perforations 50 therein, such as are usually formed by machines of this class. In Fig. 1 my device is shown as applied to the lower side of a grand piano, but by a little adaptation it can be attached to 70 instruments of other construction.

To recapitulate:—The desired number of music sheets are caused to pass through the machine, beneath the perforating devices. At the same time the striker-block is continuously rotated, and as the keys of the piano are operated the corresponding keys 75 14 are actuated to bring one or more of the plates 13 into the line of movement of the striker-blades, causing a reciprocation of 80 such plates, and a corresponding movement of the punches 6, resulting in the perforation of the sheets 34. So long as one of the plates 13 is held in a forward position, such plate will be repeatedly actuated by the blades 20, 85 in rapid succession, resulting in a corresponding rapid movement of the punch which is controlled by such plate. A simple touch of the key of the instrument will result in the contact of the plate 13 by one of 90 the striker-blades, producing a single perforation in the sheets, but if such key is held down for a greater length of time, the punch 6 will continue to operate, and by reason of the movement of the paper sheets beneath 95 the punch, will produce a perforation of corresponding length in such sheets. The movement of the striker-block is timed with reference to the movement of the music sheets so as to produce perforations therein corresponding to the length of the notes played 100 on the instrument.

It will be seen that in the operation of my device it will be possible to feed the sheets 34 through the machine continuously, instead of intermittently, as in some machines of this class. When the machine is not in use, it can be readily moved away from the instrument, the device proper being only 105 detachably attached to the instrument 110 through the engagement of the forks 31 with the keys 14. It is obvious that it can be as readily returned to an operative position by reengaging the keys 14 with the forks. When the sheets have been perforated they 115 can be separately rolled on spools at the front of the machine, ready for use, or otherwise cared for.

What I claim as my invention, and desire to secure by Letters Patent of the United 120 States, is:

1. A device of the class named, comprising a plurality of perforating devices, reciprocally mounted in the machine; a plurality of agitator plates, pivotally attached to said 125 perforating devices; a constantly rotating cylinder; a plurality of radial blades, carried by said cylinder, the outer edges of said blades being in proximity to said agitator plates; and means for bringing said agitator 130

plates severally into the line of movement of said blades, to be actuated thereby, substantially as described.

2. In a device of the class named, continuously operating striker mechanism; a plurality of agitator-plates, reciprocally mounted in the machine, in proximity to said striker mechanism; and provided with operating keys; means for holding said plates normally out of engagement with said striker mechanism; a plurality of perforating devices, controlled by said agitator-plates, and held normally out of engagement with the paper sheets to be perforated thereby; a series of bell-crank levers, suitably supported beneath the key-board of an instrument, and adapted to removably engage the keys of said agitator-plates; and means for imparting to said bell-crank levers, movement from the keys of the instrument, upon the operation thereof, to throw said agitator-plates into the line of movement of said striker mechanism, substantially as described.
3. In a device of the class named, in combination with the key-board of an instrument, a plurality of levers, fulcrumed beneath said

key-board, and adapted to be actuated by the operation of the keys of the instrument; a series of bell-crank levers, also supported beneath said keyboard, connected with said first-named levers, so as to be actuated thereby, and provided with forks at their lower ends; continuously operating striker mechanism; a plurality of agitator-plates, in proximity to said striker-mechanism, and provided with operating keys adapted to be engaged by the forks of said bell-crank levers; means for holding said plates normally out of engagement with said striker-mechanism; a plurality of perforating devices, adapted to be actuated by said agitators; and means for holding said perforating devices normally out of engagement with the paper sheets to be perforated thereby, substantially as shown and for the purpose named.

In testimony whereof, I affix my signature, in presence of two witnesses.

THEODORE M. FARLEY.
